UNITED STATES PATENT OFFICE.

HAROLD D. ARNOLD, OF MAPLEWOOD, NEW JERSEY, ASSIGNOR TO WESTERN ELECTRIC COMPANY, INCORPORATED, OF NEW YORK, N. Y., A CORPORATION OF NEW YORK.

THERMIONIC AMPLIFIER CIRCUITS.

Application filed February 3, 1919. Serial No. 274,750.

To all whom it may concern:

Be it known that I, HAROLD D. ARNOLD, a citizen of the United States, residing at Maplewood, in the county of Essex, State 5 of New Jersey, have invented certain new and useful Improvements in Thermionic Amplifier Circuits, of which the following is a full, clear, concise, and exact description.

- 10 The invention relates to repeater circuits wherein an electron-discharge device is employed for receiving comparatively weak incoming impulses and for transmitting them in the same form or in a modified form but 15 with amplified energy. Such an amplifier which has a cathode, an anode and a control member usually in the form of a grid electrode, has a very high impedance between control member and cathode which are the 20 usual input electrodes. This impedance is of the order of 25,000 ohms or more being in the nature of a space discharge path between electrodes in a vacuum. Preferably, the vacuum is as perfect as practicable, sub- 25 stantially no positive ionization taking place during the operation of the device. In case a source of potential is employed for making the potential of the grid always negative, the input circuit impedance is of the 30 order of infinity, for no electrons can flow from the filament to an electrode which is negative, so that no current flow takes place between cathode and grid even though the latter does respond to the incoming poten- 35 tial variations.

An object of the present invention is to modify the effect of this high input impedance so that it may have any desired finite value. 40 This is accomplished by connecting the incoming line to the repeater through a transformer, the secondary coil of which is shunted by a high impedance preferably a resistance of the order of 500,000 ohms, and 45 may, for instance, range from approximately 100,000 ohms to 1,000,000 ohms. This resistance is also in shunt to the input electrodes. The impedance between the input electrodes may be made much higher than 50 500,000 ohms by a battery or other source which maintains the grid negative. The impedance at the secondary side of the transformer is practically that of the 500,000 ohm resistance, as the higher impedance 55 path between the input electrodes takes

practically no current or at least a negligible current.

By this arrangement the same amplification can be secured with amplifier tubes having different input impedances, and it is 60 feasible to substitute one such tube for another in a given circuit arrangement.

More uniform amplification may also be secured by this arrangement with varying input power. In the use of amplifier circuits heretofore designed it has been found that there is a tendency for small input voltages to be amplified proportionately more than large input voltages, for the reason that the input impedance of the tube is 70 greater for small voltages than for large voltages, especially when no means is employed for maintaining the control electrode negative with respect to the cathode. By the use of a shunt path of constant resistance less than that between the input electrodes this tendency is substantially eliminated. 75

Aside from the above mentioned advantages of using the shunt impedance, it has 80 the advantage, regardless of the function of the vacuum tube or of the circuit in which it is connected, of preventing singing of the repeater in case the output and input circuits thereof are coupled either designedly 85 by an inductive coupling for instance, or accidentally by reason of the proximity of the input and output leads of the repeater.

A further advantage inherent in the use of a high impedance shunt between the line 90 and the repeater is that it is possible to employ vacuum tubes having different but high impedances in the same circuit without substantially affecting the impedance of the circuit as seen from the primary side of the 95 transformer.

This application is a continuation in part of application, Serial No. 59,210, filed November 2, 1915, and of application Serial No. 48,873, filed September 3, 1915. 100

For further details of the invention, reference may be made to the drawings in which the single figure illustrates diagrammatically a repeater circuit embodying the 105 invention.

Referring in detail to the figure, the incoming line 1 is adapted to be traversed by weak incoming impulses which are to be amplified by the amplifier 2, and to be sent out in amplified form upon the line 3. Pref- 110

erably, there is employed the battery 4 or other source which maintains the grid negative with respect to the cathode, in which case the input impedance of the repeater 5 is practically infinite, as described above. The line 1 is connected to the input electrodes of the repeater which, in this case, are the grid and cathode electrodes, by the repeating coil or transformer 5. In shunt to the secondary of the repeating coil 5 and also in shunt to the input electrodes is the impedance 6, which may be non-inductive as shown and in the form of a resistance of the order of 500,000 ohms. This resistance 10 may assume any desired form; viz, it may be a wire resistance, a lavite resistance, or a piece of paper treated with india ink and sealed in a glass tube. The battery 7 in the output circuit of the repeater supplies space current through the choke coil 8 and between cathode 9 and anode 10. If desired, the output circuit of the repeater may be coupled to the line 3 by the repeating coil 11, as shown.

25 What is claimed is:

1. The combination of a vacuum discharge repeater of the three-electrode type, an inductive coil conductively connected to the input electrodes of said repeater, and a conductive impedance in shunt to said coil.

2. The combination of an incoming line, an electric discharge repeater of the three-electrode type, a transformer coupling said line to said repeater, one coil of said transformer being conductively connected to the input electrodes of said repeater, and a conductive impedance in shunt to one of the coils of said transformer.

3. The combination of an incoming line, an electric discharge repeater of the three-electrode type, a transformer coupling said line to said repeater, the secondary coil of said transformer being conductively connected to the input electrodes of said repeater, and a conductive impedance in shunt to said secondary coil.

4. The combination of a line, a vacuum tube amplifier of the three-electrode type connected thereto, said amplifier having input terminals, means for applying a steady difference of potential between said input terminals, and a high resistance connected to said terminals.

5. The combination of a line, a vacuum tube amplifier connected thereto, said amplifier having grid and cathode electrodes, means for applying a steady difference of potential between said electrodes, and a resistance of the order of 100,000 ohms forming a by-path between said electrodes.

6. The combination of a vacuum tube amplifier having grid and cathode electrodes, means for making the potential of

said grid negative with respect to said cathode, and a high resistance by-path for said electrodes.

7. The combination of a line, a vacuum tube amplifier, a transformer for connecting said line to said amplifier, a by-path between said line and said amplifier and having an impedance of the order of 500,000 ohms, and means for maintaining the impedance of said amplifier greater than that of said by-path.

8. The combination of an incoming line, a repeater having a cathode and an anode, means for supplying a space current between said electrodes, a member for controlling said space current, means for applying a steady difference of potential between said cathode and said control member and means between said line and said repeater for making the impedance of the repeater as seen from said line, substantially of a constant value.

9. The combination of an incoming line, an amplifier having a cathode and an anode, means for supplying a space current between said electrodes, a grid electrode for controlling said space current, means for making said grid negative with respect to said cathode, and means between said line and the input electrodes for making the impedance of said amplifier as seen from said line, substantially of a constant value.

10. The combination of an incoming line, an amplifier having a cathode and an anode, means for supplying a space current between said electrodes, a grid electrode for controlling said space current, means for making said grid negative with respect to said cathode, a transformer for connecting said line to said amplifier, and a high resistance in shunt to the secondary winding of said transformer and to said grid and cathode electrodes for making the impedance of said amplifier as seen from said line, substantially of a constant value.

11. The combination of a line, an amplifier in circuit therewith having an input impedance at least as high as 100,000 ohms, and a shunt between said line and said amplifier having an impedance of an order lower than that of the input impedance of said amplifier.

12. The combination of a line, an amplifier in circuit therewith having an input impedance which is practically infinite, and a shunt between said line and said amplifier having an impedance of the order of 500,000 ohms.

In witness whereof, I hereunto subscribe my name this 15th day of January, A. D. 1919.

HAROLD D. ARNOLD.
